PROCESS FOR HYDROGENATING ALDEHYDES

Bernard H. Gwynn, Fawn Township, Allegheny County, Pa., assignor to Gulf Research & Development Company, Pittsburgh, Pa., a corporation of Delaware

Application December 30, 1950, Serial No. 203,588

7 Claims. (Cl. 260—638)

This invention relates to a process for hydrogenating aldehydes and more particularly, to a process for preferentially hydrogenating aldehydes in a mixture containing aldehydes and olefins.

Olefins are hydroformylated in the first, or hydroformylating, stage of the Oxo process. In this stage, which is also known as the oxonation or carbonylation stage, olefins react with carbon monoxide and hydrogen to produce aldehydes. Other organic reaction products such as alcohols and acetals are also produced. The product stream from the hydroformylation stage contains aldehydes, other reaction products, and in addition unreacted olefins, carbon monoxide, and hydrogen.

In the second, or hydrogenation stage of the Oxo process, aldehydes from a hydroformylation stage are converted to alcohols and other oxygenated products are also produced. However, in the previously proposed processes of which I am aware for hydrogenating aldehydes to alcohols in a mixture which also contains olefins, an important proportion of the olefins has been hydrogenated to paraffins, thus producing a mixture of hydrocarbons or a hydrocarbon fraction of the hydrogenation products consisting of a relatively smaller amount of unconverted olefins and a relatively larger amount of paraffins. It is desirable to prevent this conversion of olefins to paraffins in the hydrocarbon fraction because if the olefins in this fraction are not hydrogenated the efficiency of the Oxo process can be improved by recovering the olefins from the hydrogenation stage products and using them as such or recycling them. My invention is concerned with a process for preferentially hydrogenating aldehydes in the presence of olefins while employing conventional hydrogenation pressures such as 100 to 1,000 pounds per square inch.

I have found that aldehydes mixed with olefins can be hydrogenated to alcohols while a hydrocarbon fraction can be produced which consists chiefly of olefins by introducing water into a mixture of aldehydes and olefins, and then hydrogenating the resulting mixture in the presence of the added water over a catalyst effective at low temperatures, for example, temperatures below 500° F. When operating in this manner, aldehydes are converted to alcohols and a hydrocarbon fraction consisting chiefly of olefins is produced. The olefins can readily be separated from the alcohols and recycled to a hydroformylation stage.

I have found that it is important to carry out the process at a relatively low temperature as otherwise the olefins are hydrogenated along with the aldehydes. Concomitantly, it is important to use a catalyst which is an effective hydrogenation catalyst at low temperatures because when operating at a low temperature with a catalyst which exhibits maximum activity at a high temperature of, for example, 800° to 1,000° F., very little hydrogenation of either aldehydes or olefins occurs. On the other hand, when attempting to operate at high temperatures using a high temperature catalyst, the effect of the temperature so overbalances the effect of the added water that the hydrogenation of the olefins is not substantially prevented. As stated above, the present process is carried out at temperatures below 500° F. Preferred results are obtained at temperatures below 450°

2

F.; for example, temperatures in the range of about 300° to about 450° F. and particularly in the range of about 350° to about 400° F.

With respect to the catalysts that can be employed, in general any catalyst effective at low temperatures will be suitable for use. The so-called low temperature hydrogenation catalysts are well known in the art and only a few are mentioned by way of example. Preferred catalysts are nickel, cobalt, nickel tungsten sulfide, cobalt molybdate, and copper chromite catalysts. The catalyst can be in pelleted or granulated form and can be placed in the hydrogenation zone as such. In general, however, preferred results are obtained when the catalyst is deposited upon a carrier such as diatomaceous earth or kieselguhr.

The water can be introduced in liquid or vapor phase to the mixture of aldehydes and olefins before or after the mixture is introduced to the hydrogenation stage. Usually when hydrogenation is carried out at an elevated pressure such as at 1,000 pounds per square inch, it is more convenient to introduce water in liquid phase and to heat the mixture of hydroformylation products and water to the desired hydrogenation temperature. Part of the water can be introduced at room temperature in liquid phase into the hydrogenation reactor at intervals along the direction of flow in the reactor. In this way the temperature in the reactor can be controlled because the heat of hydrogenation is dissipated in vaporizing and heating the water to the hydrogenation temperature.

The mixture of aldehydes and olefins which is preferentially hydrogenated in accordance with the process of my invention can be obtained in a number of ways, but usually it is obtained by removing carbon monoxide and hydrogen and catalytic metals from a product stream obtained from a hydroformylation stage of an Oxo process. The mixture will therefore be identified hereafter as hydroformylation products.

The amount of water charged with the hydroformylation products to the hydrogenation zone can be varied. It is preferably to use as small an amount of water as possible and still obtain the advantages of my invention because this results in the most efficient operation of the hydrogenation reactor. Liquid volume ratios of water to hydroformylation products charged of from 0.15:1 to 2:1 give good results, and preferred results are obtained with a ratio in the range of about 0.2:1 to 0.5:1.

In order that my invention can be more readily understood, a typical method of carrying out a preferred embodiment will now be described in connection with the accompanying drawing. The single figure shows a schematic representation of a suitable plant system for carrying out the process of my invention.

A synthesis mixture of carbon monoxide and hydrogen is introduced by line 3, and a mixture of olefins and a hydroformylation catalyst, usually an iron or cobalt catalyst by line 4, to hydroformylation stage 6. The olefins and the synthesis gas are reacted and the catalytic metal salts or carbonyls are removed. Hydroformylation products containing aldehydes, other reaction products, and unreacted olefins at a pressure of about 500 pounds per square inch and a temperature of about 150° F. are removed from hydroformylation stage 6 by line 7. Water is introduced by line 8 to pump 9 and is then introduced at a pressure of about 500 pounds per square inch into the hydroformylation products by line 11. The resulting mixture of water and hydroformylation products is passed by line 12 through heat exchanger 13 wherein the mixture is heated to a temperature of about 400° F. The heated mixture is then passed from heat exchanger 13 by line 14 to hydrogenation reactor 16. The hydrogenation reactor 16 contains a number of baskets, 17a to 17f, which are packed with $\frac{1}{8}$ inch nickel on kieselguhr cat-

alyst pellets 18. The pellets which contain about 44 per cent nickel in their original state may be used as the oxide after calcining or may be partially reduced at 900° F. by passing hydrogen over them for four hours at atmospheric pressure at the rate of about 635 volumes of hydrogen per hour per volume of catalyst.

After the catalyst is prepared, hydrogen at a pressure of about 500 pounds per square inch is passed by line 19 to heat exchanger 20 in which it is heated to a temperature of about 400° F. The heated hydrogen is introduced by line 21 to the top of hydrogenation reactor 16. The mixture of hydroformylation products, water, and hydrogen passes downwardly through the hydrogenation reactor 16, the aldehydes in the hydrogenation reactor reacting with hydrogen to produce alcohols.

Additional hydrogen at a pressure of about 500 pounds per square inch and a temperature of about 100° F. is introduced beneath the catalyst baskets in the hydrogenation reactor from the hydrogen inlet line 19 by line 22 and a parallel system of valved lines, 23a to 23e. The amount of hydrogen passed through the hydrogen heater and through the various lines is controlled. In this way the heat of reaction is dissipated in heating the hydrogen, and the temperature of the hydrogenation reactor is controlled at about 400° F. At the bottom of the hydrogenation reactor substantially all of the aldehydes have been converted to alcohols but the olefins are not substantially hydrogenated.

The hydrogenation reaction products are removed from the bottom of the tower by line 26 and are passed through the heat exchanger 27 in which they are cooled to a temperature of about 120° F. The cooled hydrogenation products are passed by line 28 to pressure-reducing valve 29 where they are reduced from a pressure of about 500 pounds per square inch to substantially atmospheric pressure. The cooled depressured hydrogenation products are then passed by line 31 to hydrogen flash tower 32. Hydrogen is removed overhead in this tower by line 33. The hydrogen which is removed by line 33 is passed out of the system by line 34 and may be employed as fuel, or, if desired, the hydrogen can be recycled by line 36, pump 37, and valved line 38 to hydrogen inlet line 19.

The hydrogen-free mixture is then removed from the hydrogen flash tower by line 41 and is introduced to water separator 42. A water fraction is removed downwardly by line 43. The water fraction is recycled to water inlet line 8 by means of line 44 which contains circulatory pump 46 and valve 47. In the event a concentration of impurities such as iron oxide builds up in line 44, all or part of the water fraction can be discharged by valved line 48. When build-up of impurities is a problem, a part of the water is preferably continuously removed from the system.

A fraction containing hydrogenation products is removed overhead from water separator 42 by line 51 and is passed to separation unit 52. A fraction containing hydrocarbons consisting chiefly of olefins is removed in the separation unit by line 53. The hydrocarbon fraction can be recycled to olefin inlet line 4 by means of line 54 containing valve 55 and recycle pump 56, or, if desired, this fraction can be discharged by line 57 which contains valve 58. The fractions of hydrogenation products which boil at lower and higher temperatures than the hydrocarbons are passed by lines 61 and 62 to additional separating units which are not shown.

In order to compare results obtained when operating in accordance with the invention and when operating outside the invention, results obtained during two runs in each of a number of periods of hydrogenation are presented in Table 1 which follows. In these periods hydrogenation was carried out in a hydrogenation reactor formed by a steel pipe 0.824 inch in inside diameter surrounded by a jacket containing boiling water which was maintained at 400° F.

The hydrogenation reactor was charged with about 585

milliliters of $\frac{1}{8}$ inch nickel on kieselguhr catalyst pellets to form a bed about 6 feet long. The catalyst contained about 44 per cent nickel in its original state or 70 per cent nickel when it was calcined at 1000° F. and reduced at 900° F.

The pressure was maintained at 500 pounds per square inch during these periods. The charge to each period was hydroformylation reaction products from the same hydroformylation run to which heptenes had been charged. The hydroformylation reaction products contained 43.0 per cent oxygenated materials which were chiefly aldehydes and 57 per cent hydrocarbons which consisted of about 95 per cent olefins. The olefins in the charge were thus about 55.2 weight per cent of the charge.

Hydroformylation products were charged to the top of the hydrogenation reactor. Water, when it was added, was also charged at the top of the reactor. The hydrogenation products were removed from the bottom of the hydrogenation unit, depressured, and cooled. A portion of hydrogenation products from each run was analyzed to determine the amount of unconverted aldehydes in the hydrogenation products. Another portion of hydrogenation products from each run was distilled into a fraction containing all of the oxygenated materials and a hydrocarbon fraction containing unconverted olefins and paraffins produced by the hydrogenation of the olefins. Each oxygenation material fraction was then distilled into a subfraction containing alcohols and aldehydes and a residue subfraction. The percent alcohol was then determined by subtracting the previously determined per cent aldehydes from the total per cent alcohols and aldehydes in that subfraction. The hydrocarbon fractions were analyzed for olefins by determining bromine numbers. In the table the oxygenated materials, aldehydes, alcohols, residue, hydrocarbons, and olefins are all presented as weight per cent of the total hydrogenation products.

The efficiency of the retention of olefins in the product stream was determined by dividing the per cent olefin in the charge by the per cent olefin in the products and multiplying by a hundred. This does not take into account the slight change in weight of the hydrogenation products caused by the addition of hydrogen.

The results of the periods are given in the table which follows. The weight per cent of olefins in the hydrocarbon fraction is given at the bottom of Table 1 to show the extent to which hydrogenation of the hydrocarbon fraction is reduced by operating in accordance with my invention.

A study of the data for the runs in Table 1, in which a hydroformylation reaction product charge space velocity of 1.17 was employed in each run, shows that the addition of 0.2 liter of water per liter of hydroformylation products caused an increase in the average per cent olefins in the hydrocarbon fraction of from 57.7 per cent to 66.2 per cent. The addition of 0.5 liter of water per liter of hydroformylation products further increased the average per cent olefins to 86.3 per cent.

The advantages of my invention of preferentially hydrogenating aldehydes in a mixture of aldehydes and olefins and producing a hydrocarbon fraction consisting chiefly of olefins can be obtained while changing the conditions of operation described in Table 1. Data from a series of such periods are given in Table 2 in which hydroformylation products were passed over 200 cubic milliliters of a catalyst similar to that used for the runs of Table 1, but which was somewhat more efficient for the conversion of alcohols. In these periods a hydroformylation products charge space velocity of 0.5 and a liquid volume ratio of water to hydroformylation products charged of 0.5:1 were used. The charge and the products were analyzed in the same manner used for determining them in the periods reported in Table 1. Table 2 is as follows:

The advantages of my invention of preferentially hydrogenating aldehydes in a mixture of aldehydes and olefins

can be obtained while changing the conditions described in the tables in other ways. For example, space velocities other than 0.5 or 1.17 can be employed. Hydrogenation can be carried out at any hydrogenation pressure such as from about 100 to about 1,000 pounds per square inch. Other catalysts effective at low temperatures such as temperatures below 500° F. can be employed. Preferred results are obtained with hydrogenation temperatures below 450° F., such as 300° to 450° F., or particularly 350° to 400 F., and with nickel, cobalt, nickel tungsten sulfide, cobalt molybdate, and copper chromite catalysts. The liquid volume ratios of water to hydroformylation products in the range of 0.15:1 to 2:1 give good results; preferred results being obtained with ratios in the range of 0.20:1 to 0.5:1 liquid volume ratio.

My invention has the additional advantage that by employing it in connection with a hydroformylation stage a stream of olefins can be recovered from the hydrogenation stage which is richer in non-terminal bond olefins than the stream originally introduced to the hydroformylation stage. This occurs because the stream of olefins recovered from the hydroformylation stage is richer in non-terminal bond olefins than the stream introduced to it and because when the hydroformylation stage products are hydrogenated in accordance with the process of my invention, aldehydes are preferentially hydrogenated and the hydrocarbons in the hydrogenation stage products are chiefly olefins.

Obviously many modifications and variations of the invention, as hereinbefore set forth, may be made without departing from the spirit and scope thereof, and therefore only such limitations should be imposed as are indicated in the appended claims.

I claim:

1. A process for preferentially hydrogenating aldehydes in a mixture of aldehydes and olefins which comprises hydrogenating said mixture in the presence of added water in a liquid volume ratio of water to the mixture of aldehydes and olefins of from about 0.15:1 to about 2:1, over a low temperature hydrogenation catalyst at a temperature of about 300° to 500° F.

2. A process for preferentially hydrogenating aldehydes in a mixture of aldehydes and olefins which comprises hydrogenating said mixture in the presence of added water in a liquid volume ratio of water to the mixture of aldehydes and olefins of from about 0.15:1 to about 2:1 over a nickel catalyst at a temperature of about 300° to about 500° F.

3. A process for preferentially hydrogenating aldehydes in a mixture of aldehydes and olefins which comprises hydrogenating said mixture in the presence of added water in a liquid volume ratio of water to the mixture of aldehydes and olefins of from about 0.15:1 to about 2:1 over a cobalt catalyst at a temperature of about 300° to about 500° F.

4. A process for preferentially hydrogenating aldehydes in a mixture of aldehydes and olefins which comprises hydrogenating said mixture in the presence of added water in a liquid volume ratio of water to the mixture of aldehydes and olefins of from about 0.15:1 to about 2:1 over a nickel tungsten sulfide catalyst at a temperature of about 300° to about 500° F.

5. A process for preferentially hydrogenating aldehydes in a mixture of aldehydes and olefins which comprises hydrogenating said mixture in the presence of added water in a liquid volume ratio of water to the mixture of aldehydes and olefins of from about 0.15:1 to about 2:1 over a cobalt molybdate catalyst at a temperature of about 300° to about 500° F.

6. A process for preferentially hydrogenating aldehydes in a mixture of aldehydes and olefins which comprises hydrogenating said mixture in the presence of added water in a liquid volume ratio of water to the mixture of aldehydes and olefins of from about 0.15:1 to about 2:1 over a copper chromite catalyst at a temperature of about 300° to about 500° F.

7. A process for preferentially hydrogenating aldehydes in hydroformylation products from a hydroformylation stage which comprises introducing water into said mixture in a liquid volume ratio of water to hydroformylation products of about 0.2:1 to 0.5:1, flowing hydrogen and the resulting mixture of water and hydroformylation products at a temperature of about 350° to about 400° F. through a hydrogenation zone containing nickel catalyst, removing the resulting hydrogenation products, separating olefins from said resulting hydrogenation products, and recycling 10 said olefins to said hydroformylation stage.
